UNITED STATES PATENT OFFICE.

WILLIAM RUMBLE, JR., OF CRANFORD, NEW JERSEY.

BELT-BUCKLE.

1,099,886.

Specification of Letters Patent.

Patented June 9, 1914.

Application filed January 7, 1914. Serial No. 810,822.

To all whom it may concern:

Be it known that I, WILLIAM RUMBLE, Jr., a citizen of the United States, residing at Cranford, in the county of Union and State of New Jersey, have invented certain new and useful Improvements in Belt-Buckles, of which the following is a specification.

My present invention pertains to an improved belt buckle, the same being illustrated in the annexed drawings, in which:

Figure 1 is a longitudinal sectional view of the buckle with the locking or clamping plane in its released position; Fig. 2 a side elevation thereof, with the parts in the same relative positions; Fig. 3 a view similar to Fig. 1, showing the belt clamped or locked by the plate; Fig. 4 a side elevation with the parts in such locking position; Fig. 5 a perspective view of the buckle, as viewed from the under or inner side; and Fig. 6 a detail perspective view, illustrative of the manner of securing the ends of the cross or belt-attaching bar together.

The main object of the invention is to provide a simple and, at the same time, an efficient buckle; one which is easy of manipulation in entering the free end of the belt into operative relation therewith, and which likewise securely binds or clamps the belt when once it is adjusted.

The construction is such that a pull upon the belt only tends to cause the clamping plate to more firmly secure the belt against movement, while the belt may be readily released so that it may be drawn tighter, or the normally free end entirely withdrawn from engagement with the buckle. Again, a minimum number of parts are employed, which parts are non-separable.

The body of the buckle, formed of one piece, may be said to comprise a face plate 1, preferably made slightly convex or rounding in the direction of its length or from end to end, and from said plate extend side walls 2 and 3, the walls being parallel to each other and at substantially right angles to the face plate. As will be seen, the walls are of less height at what may be termed the entrance end of the buckle, the margin or edges of the walls merging into the slightly rounded edge or lip 4 of the adjacent end of the face plate. Each wall is provided with a slot 5, said slots lying in the same transverse plane and inclining downwardly and away from the face plate, as they recede from the lip 4. Stated in another way, the

slots may be said to converge with the face plate 1 toward the lip 4.

Extending through and freely movable in the slots 5 is a cross-pin or rod 6, having heads 6^a which bear against the outer faces of the side walls and confine the rod in place. Swiveled upon the rod is a clamping plate, comprising a body 7, having outwardly and upwardly inclined clamping wings or members 8, and at each end a downwardly-extending elongated lug 9 through which the rod 6 passes.

At what may be termed the rear end of the buckle, the side walls are formed with extensions 10, which are bent inwardly and united, forming a cross-bar to which one end of the strap 11 is designed to be secured in any suitable manner. The ends of said extensions 10 are preferably secured together in the manner best shown in Fig. 6, wherein it will be seen that one member is provided with a relatively narrow tongue 12 which is passed through a slot formed in the overlying and slightly offset portion 13 of the other member 10, the tongue being bent down, as illustrated.

The construction thus set forth at once produces a rigid structure which will not become distorted under strain, and which is also effective for the purpose designed, and easy of manipulation.

To secure the belt in place, the free end is passed inwardly past lip 4, into the space between the clamping plate and the under face of the body 1. At such time the rod 6 is drawn rearwardly in slots 5, thereby causing the clamping plate to recede from the body 1, forming a free passage-way for the belt, which is passed inwardly to the desired extent, or slightly beyond such point, whereupon a slight reverse pull upon the belt will cause the parts to assume the positions illustrated in Fig. 3. At such time the edges of the wings or member 8 will engage the belt and clamp the same against the inner face of the body 1, and the more the strain the greater the pressure, the rod 6 passing upwardly in the slots and reducing the distance between the clamping plate and the body 1. By reason of the fact that the plate is swiveled upon the rod it has a tendency to rock under the initial pulling action of the belt and as the forward wing is thrown inwardly the rear wing is thrown outwardly toward the body, causing it to contact with the belt and to be drawn for-

wardly in the direction of the pull of the belt, thereby causing the plate as a whole to move with the belt and the rod 6 to slide along the inclined slots until the belt is so 5 tightly clamped between the plate and the body that further movement is impossible.

Should the clamping plate assume the position shown in dotted lines in Fig. 1, the plate may be readily tilted to permit the 10 ready insertion of the belt-end. This is accomplished by merely pressing upon the inwardly-projecting rear wing 8, and to facilitate such operation the side walls 2 are cut away, as at 14, to permit the insertion of the 15 thumb or finger, as the case may be.

By providing the inturned lip 4 not only is a neat finish imparted to the buckle, but the lip lies close to the belt and in a measure assists in the holding action of the buckle; 20 particularly is this so where the belt is formed of thin or light material.

Having thus described my invention, what I claim is:

1. In a belt-buckle, the combination of a 25 one piece body portion comprising a face plate curved in the direction of its length; side walls extending therefrom, each wall being provided with an inclined slot, said slots converging with reference to the face 30 plate; a rod slidably mounted in said slots; a tiltable clamping plate carried by said rod, said plate being formed with wings inclining outwardly toward the inner surface of the face plate; and means for securing one

end of a belt to that end of the buckle body 35 remote from the clamping means aforesaid.

2. In a belt-buckle, the combination of a body plate; side walls extending therefrom, each of said walls being formed with a finger recess adjacent its rear end; and a tiltable 40 40 clamping plate movable toward and from the recesses, and the rear portion thereof lying adjacent said recesses when the plate is in its rearmost position.

3. In a belt-buckle, the combination of a 45 body portion comprising a face plate convexly curved in the direction of its length; an inwardly-extending lip formed at one end of said plate; side walls extending from the face plate, each wall having an inclined 50 straight slot formed therein, said slots inclining upwardly toward the face plate and lip, each of said walls likewise having a finger recess formed therein to the rear of the lower end of the slot; a rod seated and 55 slidable in said slots; a clamping plate fulcrumed upon said rod, said plate having outwardly-extending wings; and a cross bar extending from the walls at the rear end of the buckle.

In testimony whereof I have signed my name to this specification in the presence of two subscribing witnesses.

WILLIAM RUMBLE, JR.
